UNITED STATES PATENT OFFICE

MARTIN O. FIXEN, OF MINNEAPOLIS, MINNESOTA

ELECTRIC SPINNING TOP

Application filed May 5, 1927. Serial No. 188,939.

This invention relates to a spinning top and particularly to such a top which is automatically spun. While various kinds of power may be used for driving or spinning the top, the invention is illustrated as in the form of an electrically operated top. It is desirable in such a device to have a simple, comparatively inexpensive, small and compact structure and one which can be operated with a small amount of power. It is also quite desirable to have such a device arranged so that it will carry lamps or be otherwise illuminated.

It is an object of this invention, therefore, to provide a spinning top which is automatically or electrically operated.

It is a further object of the invention to provide a spinning top which is electrically operated and which carries thereon one or more lamps.

It is still another object of the invention to provide a spinning top comprising a field member and an armature member which are relatively movable, together with means for conducting electric current to the same.

It is still another object of the invention to provide an electrically operated spinning top comprising upper and lower casings which are electrically insulated and which are disposed on either side of the line.

These and other objects and advantages of the invention will be fully set forth in the following description made in connection with the accompanying drawings, in which like reference characters refer to similar parts throughout the several views and in which:—

Fig. 1 is a vertical central section through the top, certain parts being shown in side elevation;

Fig. 2 is a horizontal section taken on line 2—2 of Fig. 1, as indicated by the arrows;

Fig. 3 is a top plan view of the top;

Fig. 4 is a partial vertical section of the lower portion of the top and base shown on an enlarged scale;

Fig. 5 is a horizontal section taken on line 5—5 of Fig. 4;

Fig. 6 is a vertical section on line 6—6 of Fig. 2, as indicated by the arrows;

Fig. 7 is a vertical section on line 7—7 of Fig. 2, as indicated by the arrows;

Fig. 8 is a view in side elevation of the part shown in Fig. 2;

Fig. 9 is a detailed view of the lower portion of the armature shaft and supporting member; and

Fig. 10 is a view of a modified form of the base.

Referring to the drawings, the device comprises a base member or stand 15 which is of general frusto-conical shape and has an apertured boss at one side through which passes the downwardly extending rod 16 having an upturned vertically disposed terminal portion 16^a. The rod 16 is held in the base member 15 by the clamping nuts 17, insulating washers 15^a being disposed at each side of the member 15 and a binding post nut 19 being disposed on the outer end of rod 16. A coiled spring 20 has its lower end surrounding and supported on the rod 16 and portion 16^a thereof. A pin or rod 21 is provided having an enlarged portion 21^a adjacent its end. The portion or rod 21 below portion 21^a is disposed in the spring 20 and this spring may be connected to said portion 21^a. The portion 21^a engages at its upper side with the lower side of the bushing or sleeve member 23 of insulating material disposed centrally in and

slidable in a hub in the base 15, said sleeve 23 having a flange 23^a at its lower end preventing excessive upward movement thereof. The upper portion of rod 21 passes through and is secured to bushing 23 and has its upper end wedge shaped. The sleeve 23 has an opening therethrough in which the rod 21 is held tightly. An annular washer 25 of semi-cylindrical shape in radial cross section is adapted to be disposed over the top of base 15.

A sleeve 24 is provided having a diameter at its lower end slidable into a bore of the hub in base 15 but of greater diameter than the bore of the washer 25. The lower end of sleeve 24 is adapted to engage the top of washer 25 when the latter is in place and said sleeve has a flange 24^a a short distance above its lower end having a concave lower side and a flat upper side disposed in a plane at right angles to the axis of said sleeve. The sleeve

24 has secured therein an inner sleeve or bushing 26 of insulating material, which extends throughout the length of sleeve 24 and has a washer 26^b resting on top of the flange 24^b at the top of sleeve 24. A shaft 27 extends through sleeve 26 and has a slot 27^a in its lower end adapted to rest on top of the member 21, said lower end normally being disposed a slight distance above bushing 23. 5 The shaft 27 constitutes an armature shaft and the same has secured thereto a plurality of spaced laminated pole pieces 28 which extend radially therefrom having their outer surfaces in the surface of the cylinder and having reduced inner portions on which are disposed the armature winding 28^a. Said shaft 27 has a commutator 29 secured thereto at one side of the pole pieces 28 and has a portion extending upward above said commutator. 10 A casing member 30 having a convex lower side surrounds the lower portion of shaft 27 and stem 24 and has its lower end resting on the upper side of the flange 24^b. A washer 31 is secured in the lower end of casing 30 and supports a coiled compression spring 32 surrounding the stem or sleeve 24, the flange 24^b resting on top of said spring 32. The casing 30 has an annular flat flange 30^a at 15 its upper and outer side above which is disposed an annular insulating member or washer 33.

A field member 34 is provided, formed of laminated plates, said plates being of the form shown in Fig. 2. An upper casing 35 is 35 provided, quite similar in shape to the casing 30 which also has a flat annular flange 35^a at its outer portion. The flange 30^a, member 33, field frame 34 and flange 35^a are connected by a plurality of circumferentially spaced headed and nutted bolts 36 which pass through said parts and through flanged insulating bushings 37 extending through flange 30^a and member 33 as shown in Fig. 7. The field frame 34 has a central opening 34^a of substantially cylindrical form and a brush member 38 is secured at one side of this opening by the headed and nutted screw 39, one of the plates or corrugations 34^b of the field frame being bent outward at a right angle for receiving 40 the screw 39. Another brush 40 which, like the brush 38, is in the form of a flat resilient plate, is secured at the opposite side of the opening 34^a and is likewise secured to an upstanding portion 34^c of one of the plates of the frame 34, said brush 40 being separated 45 from the plate 34^c by insulating washers 41. The frame 34 has radially extending portions 34^d of reduced dimension on which are wound the field coils 42 and 43. It will be noted that 50 the coil 42 is connected at one end to the brush 40 and has its other end extending to and connected with the coil 43 so that said coils 42 and 43 are in series. The other end of coil 43 is connected in any suitable manner as by 55 soldering to the casing 30. The frame 34 and

flange 35^a are provided with one or more holes 34^e alining with somewhat smaller holes in the member 33. The sleeve portion of a lamp bulb 49 can be threaded through the hole in the flange 35^a so that the tip portion will engage flange 30^a. 70

A spring 44 surrounds the upper portion of shaft 27 being disposed between the end of commutator 29, and a washer 45 preferably of non-insulating material is disposed in the upper end of casing 35. As shown in Fig. 1, the casing 35 has a reduced upper end fitting about the upper end of shaft 27, and said shaft outside of said casing preferably carries a small pulley 46 secured thereto in any suitable manner as by the set screw 47, said pulley being shown as of the grooved type. The casing 30 preferably is provided with a number of holes 30^b preferably arranged in groups. The casing 15 is provided at one side with a binding post screw 50 adapted to receive a binding post nut 51. 80

A stand 52 is also provided, preferably made from sheet metal. This stand has end portions 52^a each adapted to have secured thereto a binding post 52^b and each having a semi-circular recess 52^c at its upper portion and lugs 52^d disposed at one side of the recess 52^c. One of the lugs 52^d has an aperture 52^e therein and the other has a substantially semi-circular recess 52^f. The end pieces 52^a preferably are connected by a plurality of connecting and bracing strips 52^g. 85

In operation the top will be disposed as shown in Fig. 1, the end of shaft 27 resting upon the upper end of the pin or rod 21 and the end of sleeve 24 resting lightly on the member 25. The shaft 27 is thus resiliently supported on the spring 20 and the same is kept from rotating by the slot 27^a engaging the top of rod 21 and the latter being held from rotation. Conductors extending to a small battery or other source of power are respectively connected to the binding posts formed by members 16 and 50. Current then flows from one side of the battery through the members 16, spring 20, and member 21 to the shaft 27, through this shaft to the upper casing 35 and thence to the field frame 34 to which this casing is bolted. The current 100 passes from the field frame 34 to the brush 38 which is in contact therewith and bolted thereto. Current then flows through the commutator 29 to the armature coil and thence to the other brush 40. The brush 40 as above 105 stated, is in series with the field coils 42 and 43 and the current passes through these coils and to the lower casing 30. From the lower casing the current passes into member 24 and thence to the member 15 and to the other side 110 of the battery through the binding post 50. The field frame 34 with its coils forms the field of a motor and the shaft 27 forms the armature shaft of the motor carrying the armature coils 28^a. 115

The shaft 27, as stated, also member 24 and member 26 are held from rotation, so that when current is supplied the field frame 34 rotates, carrying with it casings 30 and 35 which, it will be noted, are insulated from each other. The casings 30 and 35 and field 34 thus rotate on top of flange member 24^a and the rotation is at such high speed that equilibrium of the top is produced. It will be seen that the top has considerable weight above the member 25 and will not stand up until it is rotated at sufficient speed. The field member 34, also casing members 30 and 35 thus spin on top of flange member 24^a and will continue to spin as long as current is supplied. Insulating member 26 is tightly fitted around member 27, and sleeve 24 is fitted tightly around member 26.

It will be seen that the lamp bulbs 49 have their shell portions in contact with the casing 35 and the tip portions in contact with the casing 30. Current is thus supplied to these lamp bulbs which are illuminated and the top revolving at high speed, a circle of light is produced, giving a very pleasing effect. The lamps 49 can, of course, be disposed in different places and at different heights in respect to the top and bottom of the top. The holes 30^b in the casing may be arranged so that the top will produce a humming or singing sound when operated. If the washer 25 is removed from base 15, the end of sleeve 24 may extend down into the hub of the base 15 and the top will then be supported in vertical position by said base when in operative or inoperative position. The shaft 27 will force the bushing 23 further down in the base and compress spring 20. The top may also be disposed in the stand 52, the end 24^a of sleeve 24 being disposed in the opening 52^a and the pulley being disposed in the recess 52^b. The friction of the grooved pulley 46 and the edge of recess 52^b will prevent rotation of the shaft 27 but the casings 30 and 35 and frame 34 will thus revolve when current is supplied to the binding posts on the frame 52. It will be noted that the end portions of frame 52 are insulated from each other by insulation 53 between the connecting strips 52^c, and said ends. The direction of rotation of the top may be reversed by reversing the location of brushes 38 and 40.

The top can also be disposed in the recesses 52^c. The cylindrical end portions of the casings 30 and 35 will rest in the recesses 32^c. When so disposed, the casings 30 and 35 are held from rotation by friction with the edges of recesses 52^c, the field frame thus also being held from rotation. The armature shaft 27 thus revolves and with the top in this position, the same can be used as a motor and a small belt run from pulley 46 for operating some toy if desired.

From the above description it is seen that

applicant has provided a very simple, efficient and highly entertaining automatic or electrical top. The device is very entertaining and the same is simple and durable in construction. The same can be made at comparatively small expense and will have a high degree of utility for the purpose intended. The device has been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. An electric spinning top having in combination, a spindle, means for conducting current to said spindle including means engaging the end of said spindle for holding the same against rotation, an armature carried by said spindle, a casing having a portion surrounding said spindle and armature and insulated from said spindle, means for supporting said casing for rotation, a field frame having a field winding thereon secured to said casing and insulated from said portion thereof, said casing having a portion engaging said shaft and engaging and connected to said field frame, a commutator carried by said armature and brushes carried by said field frame engaging said commutator.

2. A spinning top having in combination, a spindle, a casing mounted for rotation relative to said spindle, said casing having two parts, means for electrically separating said parts, means for conducting electric current to said spindle and casing whereby the portions of said casing are connected to the two sides of the electric circuit, and means for holding a lamp bulb in position with the shell engaging one portion of said casing and the tip engaging the other portion so that said bulb will be illuminated.

3. An electric spinning top having in combination, a spindle, a casing surrounding said spindle and mounted for rotation relative thereto, said casing having portions electrically insulated from each other, a lamp support extending between said portions and means for conducting electric current from one of said portions to another and through a lamp socket held in said support.

4. A spinning top having in combination, a spindle, a sleeve surrounding one end of said spindle and insulated therefrom, a base member for supporting said sleeve about a vertical axis, means in said base member yieldingly engaging the end of said spindle for holding the same against rotation and conducting cur-

- rent thereto, a casing engaging said sleeve, a field frame secured to and insulated from said casing, a second casing secured to said field frame in electrical contact therewith and 5 engaging the other end of said spindle, an armature winding carried by said spindle, a commutator carried by said spindle co-operating with said winding, brushes carried by said field frame engaging said commutator, one 10 of said brushes being connected to said frame and one of said brushes being insulated from said frame, a field winding connected to said latter brush and to said first mentioned casing.
- 15 5. A spinning top having in combination, a spindle, means for yieldingly engaging said spindle for conducting current thereto, a casing mounted for movement relatively to said spindle and having a portion insulated from 20 said spindle, a support in electrical contact with said portion, a member for supporting said support for rotation about a vertical axis and electrical means for causing relative rotation between said spindle and casing.
- 25 6. A spinning top having in combination, a base member, a member extending into said base and insulated therefrom, yielding means engaging said last mentioned member, a rod supported on said yielding means, a spindle 30 non-rotatively engaging said rod, an armature carried by said spindle, a field carrying member surrounding said armature, a casing carried by said field member and surrounding said spindle, and means electrically connected 35 with a portion of said casing adapted to be supported on said base and in electrical contact therewith, and means for supplying electric current to said first mentioned member and said base whereby said casing and spindle are relatively rotated.
- 40 7. An electric spinning top having in combination, a spindle, an armature carried by said spindle, a commutator on said spindle in connection with said armature, means for engaging one end of said spindle for holding the same against rotation and supplying electric current thereto, a casing surrounding said spindle and insulated therefrom, means for supporting said casing for rotation about a 45 vertical axis, a field frame secured to and insulated from said casing, a second casing secured to said field frame similar to said first mentioned casing but oppositely disposed and in electrical contact with said field frame and 50 with said second casing, brushes engaging said commutator and a field winding for said field frame whereby when current is supplied to said spindle and first mentioned casing, said casings and spindle will be relatively rotated.
- 55 8. The structure set forth in claim 7, said field winding being a series winding connected with one end of said first mentioned casing and at its other end to one of said 60 brushes, said brushes being carried by said field frame, said latter brush being insulated from said frame and the other brush being electrically connected thereto.
9. A spinning top having in combination, a spindle, a casing surrounding said spindle having upper and lower portions, a field frame to which said casings are secured, an armature carried by said spindle, a commutator connected to said armature, brushes engaging said armature carried by said field frame, a winding for said field frame, a base member, means engaging the end of said spindle, means supporting said casing on said base, and insulating means so disposed that an electric current is conducted through 70 said last mentioned means but one, to said spindle, the upper portion of said casing, said field frame, one of said brushes, said commutator and armature, the other of said brushes, said field winding, the lower part of said casing, and to said last mentioned means and base.
- 75 10. An electric spinning top having in combination, a spindle member, a frame member, an armature secured to one of said members and a field coil secured to the other of said members, means engaging one of said members and holding the same against rotation, means for supporting the other member for rotation about a substantially vertical axis, a conductor connected to one of said means for supplying current to said armature, and a conductor connected to the other of said means for supplying current to said field coil.
- 80 11. A spinning top having in combination, a spindle, a casing mounted for movement relatively to said spindle, means for supporting said casing for rotation about a vertical axis, means carried by said support 85 on which one end of said spindle rests, the same holding said spindle against rotation in a vertical position with its other end unsupported, and means for causing relative rotation between said spindle and casing for 90 maintaining said top in equilibrium about a vertical axis.
- 95 12. A spinning top having in combination, a spindle, a casing mounted for movement relatively to said spindle and having a portion insulated from said spindle, means for supporting said casing about a vertical axis adapted to make electrical contact therewith, means engaging one end of said spindle while in vertical position for preventing rotation thereof, making electrical contact therewith the other end of said spindle being unsupported electrical devices for causing relative rotation between said spindle and casing to hold the same in equilibrium about 100 a vertical axis, and conductors connected respectively to said last two mentioned means for supplying current to said devices through said spindle and casing respectively.
- 105 130

13. A spinning top having in combination,
a spindle member, a frame member, electrical
means for causing relative rotation between
said members, a base including supporting
means for supporting one of said members
about a substantially vertical axis, and in-
cluding means yieldingly engaging the end
of the other member and holding the same
against rotation, a contact member carried
by said base and electrically connected with
said yielding means, and another contact
member carried by said base and connected
to said supporting means whereby current
can be supplied to said electrical devices and
said spindle and member supported for rela-
tive rotation.

14. A spinning top having in combination,
a spindle member, a casing surrounding said
spindle member, electrical means for caus-
ing relative rotation between said members,
means for supporting said casing for rotation
about a vertical axis, means engaging and
supporting one end of said spindle in a ver-
tical position and preventing rotation there-
of, and conductors connected respectively to
said spindle and casing for actuating said
first mentioned means.

In testimony whereof I affix my signature.
MARTIN O. FIXEN.
